UNITED STATES PATENT OFFICE.

HARRY T. GAUSS, OF CHICAGO, ILLINOIS.

DESIGN FOR A TIRE.

55,420.

Specification for Design.

Patented June 8, 1920.

Application filed March 15, 1920. Serial No. 366,118. Term of patent 14 years.

To all whom it may concern:

Be it known that I, HARRY T. GAUSS, a citizen of the United States, residing at Chicago, in the county of Cook and State of Illinois, have invented a new, original, and ornamental Design for Tires, of which the following is a specification, reference being had to the accompanying drawings, forming a part thereof.

In said drawings:

Figure 1 is a plan view of a tire showing my new design; and

Fig. 2, is a face view of a tire showing my new design, but upon an enlarged scale.

I claim:

The ornamental design for a tire substantially as shown.

HARRY T. GAUSS.
